UNITED STATES PATENT OFFICE.

CHARLES L. PAULUS AND ROBERT KAUCH, OF DAYTON, OHIO.

BOMB-RELEASE MECHANISM.

Application filed May 19, 1924. Serial No. 714,495.

This invention relates to improvements in bomb release mechanisms.

The principal object of the invention is to provide a release mechanism which is positive in operation and is in the form of a unit capable of use with various types of bomb racks having different numbers of bomb-carrying stations and differently arranged. It is a further object to provide a mechanism of the character described wherein release members are set according to different loadings of bombs and are arranged to be actuated in proper order to release the bombs.

The invention is described in the following specification, in which reference is made to the accompanying drawing, wherein:

Fig. 1 is a view of a bomb rack of the internal type equipped with a release unit in accordance with the present invention.

Fig. 2 is an enlarged view of the release unit partly in section and partly in elevation.

Fig. 3 is a diagrammatic perspective illustrating the use of the release mechanism.

Fig. 4 is a fragmentary isolated sectional detail of a part of the mechanism.

Throughout the views the same reference numerals are applied to the same parts.

The invention is applied to bomb racks of either the external or internal type, having any usual number of bomb-carrying stations. In the present case, Fig. 1 illustrates an internal type bomb rack 10 having tiers capable of loading twenty one-hundred-pound bombs 11. The release mechanism is shown mounted on the rack at 12, and flexible control wires 13, extending thru flexible conduits or the like, are concentrated to the unit 12, where they are controlled to operate the latches in the rack to release the bombs in order. The unit of the present invention is applicable universally to bomb racks of all standard types having different numbers of stations and the wires 13, corresponding in number to the number of stations in a given rack are extended to the unit and there connected with the release members in order, the unit having at least as many release members as the rack has stations. It is contemplated further to use the unit with a bomb rack having a certain number of stations and, by placing the proper release members in cocked position when a certain loading of bombs has been placed in the rack, to release various loadings in order. In

this way a rack for, say twenty one-hundred pound bombs, can be loaded with a smaller number of larger bombs also if desired. The dotted circles 14 represent four large bombs loaded in the rack in place of sixteen smaller bombs, the entire loading including in this case, four large bombs and four small bombs. These bombs are held by latches in the usual manner, and the release mechanism of the present invention enables dropping the same in order, as will presently be described. Various other loadings can be accommodated within the limits of the rack, and may be dropped similarly in order as desired.

The release mechanism 12 comprises a plurality of release levers 15 pivoted on a shaft 16 mounted in the casing 17. The levers 15 have notches 18 in the inside of the bearings 19 thereof, spaced 90° apart. The shaft 16 is fixed by means of a pin 20 in the casing 17, and has a plurality of spring-pressed detents 21 which are arranged to engage in the notches 18 to secure the levers 15 in either cocked or uncocked position. In Fig. 3, four levers are shown in cocked position, the remainder being in uncocked position. The control wires 13 are threaded through openings 22 in the wall of the casing 17, as shown in Fig. 2, and separate, passing over suitable pulleys or thru flexible conduits and guides in the frame of the rack 10 as indicated in Fig. 1, to be connected with the latches supporting the bombs. With the levers 15 in cocked position as shown, the latches are closed and when the levers are operated to the uncocked or released position, the control wires are pulled and the latches opened to release the bombs.

The levers 15 are arranged to be operated by the rotary movement of a disc 23 slidable on a square shaft 24. The disc 23 has a pin 25 extending from one side of a lug 26 on its periphery which is arranged to ride in and out of a radial slot 27 in the side of the bearings 19 of the levers 15. The bearings 19 it will be seen, are formed as a sector of a Geneva gear comprising two teeth 28 and 29 on opposite sides of the slot 26, having arcuate faces to fit the edge of the disc 23. The tooth 28 is blank and is turned up when the lever 15 is moved to released or uncocked position. This tooth serves to guide the disc 23 past and prevents its turning by having the lug 26 engaging the edge thereof, the edges of two contiguous teeth

28 being flush when in uncocked position. The tooth 29 has a web 30 extending cross-wise of its arcuate face which, when the levers 15 are placed in cocked position in 5 the manner shown in Fig. 3, serve as stops at the cocked stations of the release mechanism to halt the disc 23 as the latter moves across the top of the levers in sliding on the shaft 24. The intermediate uncocked levers 10 present their blank teeth 28 upward and permit the passage thereover of the disc 23. In other words, the disc 23 will operate only upon levers which have been placed in cocked position, and any one or more of the 15 levers may be selected depending on what stations are loaded. The cocked levers are all operated in order so that the bombs lowermost in the rack are dropped first. From an inspection of Fig. 3, it will appear that 20 rotation of the disc 23 in a clockwise direction will cause the pin 25 on the lug 26 to enter the slot 27 and rotate the Geneva gear sector to swing the lever 15 to released position. The bearings 19 are cut away as 25 at 31 in front of the slot 27 to accommodate the lug 26 as the pin 25 enters the driving slot 27, in turning the gear and swinging the lever. The edges of the teeth 28 and 29 of the gear sector enter the recess 32 in 30 the periphery of the disc 23 as the gear is turned. When the lever is in released position, it is held by the detent 21 riding into the notch 18.

The disc 23 is rotated in the turning of 35 the shaft 24 by a sprocket 33 fixed on the end of the shaft 24 projecting from the casing 17. This sprocket is operated in the usual manner by a chain extending to a manually operated sprocket (not shown) in 40 the bomber's cockpit. The latter usually has a form of ratchet to cause the turning thereof to be in one direction. A compression spring 34 coiled about the shaft 24 inside the casing 17 serves to urge the disc 23 45 in one direction to move it from one cocked lever to the next after a lever is operated to release a bomb. The intermediate release levers held by the spring-pressed detents 21 offer no obstruction to the disc in its movement to the next cocked lever.

From the foregoing it is apparent that we 50 have provided a release mechanism capable of general application to a great variety of types and sizes of bomb racks and that the 55 mechanism is absolutely positive in its operation in the absence of any defective or broken parts. In former types of release mechanisms a common annoyance arose thru the release members missing and the 60 bomber frequently was at a loss to know whether a bomb was released. This usually or invariably was due to the actuating part being capable of movement in between stations, and occurred usually when the bomber 65 operated the release lever so quickly the

actuating part had not arrived at the next cocked station, or where the parts became jammed. In the present structure this disadvantage is remedied by preventing the manual operation of the actuating part 70 before it arrives at a cocked station. Aside from the advantage of compactness gained in the present structure by concentrating the release wires to a single remote point for operation, there is the advantage also that 75 the parts can conveniently be encased to be kept free of dirt and can be operated in a bath of oil, if desired. All of the features of operation possible in previous types of release mechanisms are likewise possible 80 with the present mechanism, as was pointed out above.

We claim:

1. In a bomb rack, bomb carrying stations arranged in several tiers in said rack, flexible bomb release wires extending from said stations in each tier to a common remote point for operation, and a single encased release device at said point having all of said wires concentrated thereto, said device comprising a plurality of release members to have connection with said wires and placed in cocked position when said stations are loaded, there being as many or more release members than the rack has stations whereby to enable universal application of the unit on different installations of racks having different loading capacities and means to operate said members in order.

2. The combination in a device of the 100 character described of a plurality of parts to be operated disposed in a row and arranged to be set in cocked position, a manually rotated member movable along the row from one cocked part to the next to operate 105 the same in order, and means preventing the manual rotation of said member except when the same is in position at a cocked part.

3. The combination in a device of the 110 character described, of a plurality of parts to be operated disposed in a row and arranged to be set in cocked position, a manually rotated member movable along the row from one cocked part to the next to operate 115 the same in order, and means preventing the manual rotation of said member except when the same is in position at the cocked part, comprising a portion on said parts exposed to said member when in uncocked position.

4. The combination in a device of the character described, of a plurality of parts to be operated disposed in a row and arranged to be set in cocked position, and an 125 actuating member movable along the row and rotatable to actuate the cocked parts in succession, said member being prevented from rotating when between parts.

5. The combination in a device of the 130

- character described; of a plurality of parts to be operated, disposed in a row, and arranged to be set selectively in cocked position, and an actuating member movable 5 along the row and rotatable to actuate the cocked parts successively, said member being movable freely past the uncocked parts and prevented thereby from rotating.
6. The combination in a device of the character described, of a plurality of parts to be operated, disposed in a row and arranged to be set selectively in cocked position, an actuating member movable along the row and rotatable to actuate the cocked parts 10 successively, and means moved into position when said levers are moved to uncocked position serving to prevent rotation of said actuating member when the same is adjacent thereto.
15. The combination in a device of the character described, of a continuously rotatable driver movable axially, a plurality of parts pivotally mounted in a row in the path of said driver to be operated thereby in succession, and a Geneva gear portion on each 20 of said parts to be engaged by said driver.
25. The combination in a device of the character described, of a continuously rotatable Geneva disk movable axially, a plurality of levers pivoted in a row in the path of said disk, each having a two toothed Geneva gear thereon to be engaged by said disk.
30. The combination in a device of the character described, of a continuously rotatable Geneva disk movable axially, a plurality of levers pivoted in a row in the path of said disk, each having a two toothed Geneva gear thereon to be engaged by said disk.
35. The combination in a device of the character described, of a continuously rotatable Geneva disk movable axially, a plurality of levers pivoted in a row in the path of said disk, each having a two-toothed Geneva gear thereon to be engaged by said disk, one of said teeth serving as a driving tooth and the other as a stop for guiding the driver past the lever without operating the same, the first tooth being exposed to 40 said disk in the cocked position of said lever and the second in the released or unlocked position, and detent means to hold said lever in either position.
45. The combination in a device of the character described, of a continuously rotatable Geneva disk movable axially, a plurality of levers pivoted in a row in the path of said disk, each having a two-toothed Geneva gear thereon to be engaged by said disk, one of said teeth serving as a driving tooth and the other as a stop for guiding the driver past the lever without operating the same, the first tooth being exposed to 50 said disk in the cocked position of said lever and the second in the released or unlocked position, and detent means to hold said lever in either position.
55. The combination in a device of the character described, of a continuously rotatable Geneva disk movable axially, a plurality of levers pivoted in a row in the path of said disk, each having a two-toothed Geneva gear thereon to be engaged by said disk, one of said teeth serving as a driving tooth and the other as a stop for guiding the driver past the lever without operating the same, the first tooth being exposed to 55 said disk in the cocked position of said lever and the second in the released or uncocked position.
60. The combination in a device of the character described of a rotary Geneva gear disc, a pivoted lever and a Geneva gear sector on said lever to be operated by said disc to swing said lever.
65. The combination in a device of the character described, of a rotary Geneva gear disk, a pivoted lever, and a Geneva gear sector on said lever comprising two teeth, one being conformed blank to prevent rotation of said disk when the same is brought into position and the disk moves adjacent thereto, and the other being conformed to receive the driving pin of said disk to swing said lever in the rotation of said disc.
70. The combination in a device of the character described, of a rotary Geneva gear disk, a pivoted lever, and a Geneva gear sector on said lever comprising two teeth, one tooth having a blank face serving as a guide to cause the disk to move past and serving also to prevent rotation thereof, and the other tooth having its face conformed to provide a stop for said disk to halt the same when it arrives adjacent thereto and being further conformed to permit rotation of said disk to drive said gear sector and swing said lever.
75. The combination in a device of the character described, of a continuously rotatable Geneva disk movable axially, a plurality of levers pivoted in a row in the path of said disk each having a two toothed Geneva gear thereon to be engaged by said disk, one of said teeth serving as a driving tooth and the other as a stop for guiding the driving disk past the lever without operating the same, the first tooth being exposed to 80 said disk in the cocked position of said lever and the second in the released or unlocked position, and detent means to hold said lever in either position.
85. The combination in a device of the character described, of a continuously rotatable Geneva disk movable axially, a plurality of levers pivoted in a row in the path of said disk each having a two toothed Geneva gear thereon to be engaged by said disk, one of said teeth serving as a driving tooth and the other as a stop for guiding the driving disk past the lever without operating the same, the first tooth being exposed to 90 said disk in the cocked position of said lever and the second in the released or unlocked position, and detent means to hold said lever in either position.
95. The combination in a device of the character described, of a rotary Geneva gear disk, a pivoted lever, and a Geneva gear sector on said lever comprising two teeth, one being conformed blank to prevent rotation of said disk when the same is brought into position and the disk moves adjacent thereto, and the other being conformed to receive the driving pin of said disk to swing said lever, and detent means to hold said lever yieldingly with either tooth 100 in position.
100. The combination in a device of the character described, of a continuously rotatable Geneva disk movable axially, a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth 105 being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.
110. The combination in a device of the character described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.
115. The combination in a device of the character described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.
120. The combination in a device of the character described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.
125. The combination in a device of the character described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.
130. The combination in a device of the character described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being webbed crosswise of the arcuate face thereof to provide a stop and being conformed to be meshed with to turn said gear and swing said lever, and a rotary Geneva disk movable along the row of levers, arranged to pass by the blank teeth of the uncocked levers and be stopped by the webbed teeth of the cocked levers in order and to operate the latter.

acter described, of a plurality of levers pivoted side by side in a row adapted to be set selectively in cocked position and when so set to be operated to uncocked or released position, each of said levers having two arcuate faced Geneva gear teeth thereon with a driving slot between, one of said teeth being blank and being turned up when said lever is in uncocked position, and the other tooth being 10 webbed crosswise of the arcuate face thereof to provide a stop and being conformed to be meshed with to turn said gear and swing said lever, and a manually turned Geneva disk movable along the row of levers, arranged 15 to pass by the blank teeth of the uncocked levers and be stopped by the webbed teeth of the cocked levers in order and to operate the latter, said disk being held against turning when adjacent the uncocked levers and being free to turn only when it engages a web on a cocked lever, when its driving pin is free to enter a driving slot.

18. The combination in a device of the character described, of a plurality of levers pivoted side by side in a row adapted to be set selectively in cocked position and when so set to be operated to uncocked or released position, each of said levers having 25 two arcuate faced Geneva gear teeth thereon, with a driving slot between, one tooth being blank and being turned up when said lever is moved to released or uncocked position, a rotary Geneva gear disk having a lug projecting 30 from the periphery thereof having a driving pin thereon, said disk being guided by said blank tooth to pass freely thereover and being held from rotation by its lug engaging thereon, the other tooth being webbed 35 across the arcuate face thereof to provide a stop to halt said disk when turned up in its path in the cocked position of said lever, and being conformed to receive the lug of said disk and permit its rotation so that 40 the driving pin of said disk enters the driving slot of said lever to swing the same.

19. The combination in a device of the character described of a plurality of parts to be operated disposed in a row and arranged to be 45 set selectively in a cocked position, a manually rotated member moving along the row from one cock to the next progressively to operate the same in order, and means preventing the manual rotation of said member except when the same is in position at a cocked part and preventing further rotation at a cocked part unless the latter is operated to a certain predetermined position.

20. The combination in a device of the character described of a plurality of parts to be operated disposed in a row and arranged to be set selectively in a cocked position, a manually rotated member moving along the row from one cocked part to the next progressively for operating said parts

in order, spring means for progressing said member from one cocked part to the next from one end of the row to the other, and means preventing the manual rotation of said member in between cocked parts. 70

21. In an apparatus of the character described where a plurality of similar mechanisms are grouped together for support and successive operation by a single operating member, the combination of a series of mechanisms, a single operating member therefor, a plurality of operated parts stationed together in flush relation with one another, said parts when in cocked position serving to stop said operating member, which when operated serves to actuate the mechanism associated with the cocked part and said parts when in uncocked position serving as guides for the free movement thereof of said operating member whereby the latter moves from one cocked part to the next, said uncocked parts serving to prevent operation of said operating member. 80

22. In an apparatus of the character described where a plurality of similar mechanisms are grouped together for support and successive operation by a single operating member, the combination of a series of mechanisms, a single operating member therefor, a plurality of operated parts stationed together in flush relation with one another, said parts when in cocked position serving to stop said operating member, which when operated serves to actuate the mechanism associated with the cocked part and said parts when in uncocked position serving as guides for the free movement thereof of said operating member whereby the latter moves from one cocked part to the next, said uncocked parts serving to prevent operation of said operating member, each of said cocked parts being capable only of a predetermined movement under the operation of said operating member, and when moved the predetermined amount serving, like other uncocked parts, 90 to guide the operating member to the next cocked part. 95

23. In an apparatus of the character described where a plurality of similar mechanisms are grouped together for support and successive operation by a single operating member, the combination of a series of mechanisms, a single operating member therefor, a plurality of operated parts stationed together in flush relation with one another, said parts when in cocked position serving to stop said operating member, which when operated serves to actuate the mechanism associated with the cocked part and said parts when in uncocked position serving as guides for the free movement thereof of said operating member, whereby the latter moves from one cocked part to the next, said uncocked parts serving to prevent operation of said operating member, each 100 110 120 125 130

of said cocked parts being capable only of a predetermined movement under the operation of said operating member, and when moved the predetermined amount serving, like other uncocked parts, to guide the operating member to the next cocked part, and spring means urging said operating member

from one cocked part to the next progressively.

In testimony whereof we affix our signatures.

CHARLES L. PAULUS.
ROBERT KAUCH.
